mesne assignments, to Jack Galter, Chicago,
Ill.

Application August 21, 1941, Serial No. 102,979

Term of patent 14 years

To all whom it may concern:

Be it known that I, George L. Lawrence, a citizen of the United States, residing in Peru, in the county of Miami and State of Indiana, have invented a new, original, and ornamental Design for a Camera, of which the following is a specification, reference being had to the accompanying drawing, forming a part thereof.

In the drawing, Fig. 1 is a perspective view of the camera showing my new design;

Fig. 2 is a plan view thereof;
Fig. 3 is a side elevational view thereof;
Fig. 4 is a front elevational view thereof;
Fig. 5 is a back elevational view thereof.
I claim:
The ornamental design for a camera, as shown.

GEORGE L. LAWRENCE.
